UNITED STATES PATENT OFFICE.

WARREN WHEELOCK, OF NEW YORK, N. Y.

DESIGN FOR AN ANDIRON.

60,888.

Specification for Design. Patented Apr. 18, 1922.

Application filed March 5, 1921. Serial No. 450,094. Term of patent 3½ years.

To all whom it may concern:

Be it known that I, WARREN WHEELOCK, a citizen of the United States, residing at 131 Macdougal Street, in the city, county, and State of New York, borough of Manhattan, have invented a new, original, and ornamental Design for Andirons, of which the following is a specification, reference being had to the accompanying drawings, forming a part thereof, in which—

Fig. 1 is a side view in perspective of an andiron, and Fig. 2 is a front view in perspective of same, both showing my new design.

I claim:

The ornamental design for an andiron as shown.

WARREN WHEELOCK.
